CHARLES SPAETH, OF FLUSHING, NEW YORK, ASSIGNOR TO NE-ARGA CORPORATION, OF NEW YORK, N. Y., A CORPORATION OF NEW YORK

LAMP STARTING DEVICE

Application filed January 18, 1930. Serial No. 421,681.

This invention relates to starting devices for mercury arc lamps and similar apparatus.

It is an object of my invention to provide a starting arrangement for mercury arc lamps or similar electrical discharge devices, that is so arranged as to be operative for but a relatively short period of time after energizing current is supplied to the device in which the starting arrangement is associated.

10 In the production of talking moving pictures it is important to have, as nearly as possible, a complete absence of all unnecessary noises and electrical disturbances. Mercury arc lamps equipped with starting devices of 15 the type known heretofore, are unsuitable for use in the production of talking pictures because when one of the lamps becomes extinguished the starting device thereof immediately starts to function so as to reignite the 20 lamp, thereby producing a clicking noise. The noise produced by the ordinary starting device is sufficient to cause a serious disturbance, which will be made part of the sound record. Likewise, when the starting device serves to create 25 a momentary high potential starting current, the starting current causes a disturbance in the recording of the sound, if an electrical process is being used. This recording is usually carried out by electrical recording 30 apparatus including a high power amplifier which serves to amplify the sound currents picked up through microphones. These amplifiers are sufficiently powerful to pick up the disturbing electrical waves as well, thereby 35 impressing on the recording medium an undesired noise.

In accordance with my invention I provide time controlled means which, a short interval after application of an operating potential to the lamp renders inactive the starting mechanism so that if the lamp becomes extinguished thereafter the starting device will be unable to function. The lamp will therefore remain unlit until it is manually 40 restored to operation at an opportune moment. I accomplish this result by providing a thermostatic switch, the operating element of which gradually becomes heated after the closing of the main line switch of 45 the lamp so that after a short interval of 50

time the contacts of the thermostatic switch are opened. These contacts are connected in the current energizing line of the automatic starting device so that said device is rendered inoperative for the opening of the contacts just mentioned.

The objects and advantages of my invention and the manner of attaining them will be made clear in the following description and accompanying drawing.

In the drawing, reference numeral 1 indicates an electrical discharge illuminating tube which may be either of the type disclosed in my copending application Serial No. 343,873, filed March 2, 1929 or of the ordinary mercury arc type. As shown in the drawing the envelope is provided with an alkaline metal cathode 2, an anode 3, and an auxiliary electrode 4 of mercury. Current from a power source is supplied to the device through the main conductors 5 and 6 which may be joined to a direct current line. Serially connected in one of the main conductors is a control switch 7 which serves to open or close the energizing circuit of the tube 1. When this switch is closed current flows from the conductor 5 through the switch, the control resistances 8 and 9 through the tube 1 and back to the supply line over the conductor 6. With devices of the type mentioned above, starting current is needed, the potential of which is higher than is necessary for the normal operation of the device. This high potential is supplied by means comprising an inductance coil 10, inserted in series with one of the supply conductors, and provided with a make and break control switch 11 of the mercury or any other suitable type. The entire starting mechanism comprising the inductance coil 10 and switch 11 may be of any well known type and hence need not be described more in detail. When the main line switch 7 is closed the current passes by means of a wire 12 through a thermostatic switch 13, current limiting resistance 14, switch 11, coil 10 back of the other side of the line. As soon as the current passes through the inductance coil, core 15 thereof becomes magnetized, attracting the pivotally mounted armature 16 and causing the contact of 100

switch 11 to be opened. The supply circuit of the coil 10 now being broken a high inductive potential is applied across the tube 1 thereby ionizing the gas therein and initiating operation. If the tube 1 does not start operating on the first break of the switch 11 the armature 16 is immediately tilted back to its original position by any suitable means such as spring 17, whereby the contacts of switch 11 are again closed and the operation repeated until the discharge through the lamp is permanently established. During the time the starting mechanism is operating a current passes from the wire 12 through the heating resistance 18 back to the other side of the line. This heating element 18 serves to heat the thermostatic element of the switch 13 thereby causing the contacts thereof to open after a short interval of time. This interval is made long enough by the proper selection of the heating element 18 to allow for the starting of the tube 1 by the mechanism already described. The period is made sufficiently long to enable the starting mechanism to operate several times if necessary in order to create a self-sustaining discharge through the tube. After the current has been on for a slightly longer interval of time, the contacts of the thermostatic switch 13 are opened and maintained open by the heating effect of the element 18, which is, as clearly shown in the drawing, shunted across the main line. The result of this is that if the tube 1 becomes extinguished for any reason after having been put in operation, the starting mechanism thereof is unable to function until the main line switch 7 is opened so as to allow the thermostatic switch 13 to cool off and close its contacts. Therefore no undesired operation of the starting mechanism can take place, and absence of disturbing noises and electrical waves is insured. The function of condenser 19 is to prevent arcing at the contacts 11 and thereby increase the potential created by the coil 10. While but a single lamp is shown in the drawings several lamps might be controlled by a single thermostatic switch 13. In this case each of the several starting mechanisms would be so connected as to have its operating circuit broken by switch 13.

It will be obvious to those skilled in the art that the invention is capable of a wide variety of modifications and adaptions and that the present disclosure is intended merely to illustrate its nature without limiting its scope, which is defined in the claims.

What I claim is:

1. In a lighting system, a source of energizing current, an illuminating tube requiring a high starting potential, starting means for creating said potential and an auxiliary means for rendering said starting means inoperative until the main supply current is cut off after the expiration of a certain in-

terval of time from the application of the energized current.

2. A device in accordance with claim 1 wherein the auxiliary means comprises a thermostatic switch having the contacts thereof connected in a series with a starting mechanism and having a heating element connected directly to the source of energizing current.

3. In a lighting system, an electrical discharge illuminating tube, an automatic inductive starting device therefor, an operating circuit, an energizing circuit for said starting device, a pair of switch contacts in series with said energizing circuit and thermostatic means for opening said contacts a short interval of time after the application of an energizing potential to said system.

In testimony whereof, I have signed my name to this specification, this 16th day of January, 1930.

CHARLES SPAETH.
